UNITED STATES PATENT OFFICE.

GUSTAV JOSEF DOLLINER, OF HAMBURG, GERMANY, ASSIGNOR TO JOSEF STEINDECKER, OF SAME PLACE.

WINDOW.

SPECIFICATION forming part of Letters Patent No. 404,179, dated May 28, 1889.

Application filed July 11, 1888. Serial No. 279,663. (No model.)

To all whom it may concern:

Be it known that I, GUSTAV JOSEF DOLLINER, manufacturer, of Hamburg, in the Free State of Hamburg and German Empire, have 5 invented a new and useful Improvement in Hinged Casements, of which the following is a specification, reference being had therein to the accompanying drawings.

My invention relates to an apparatus for 10 opening windows outside and inside of the room.

Figure 1 shows a view of the improved window as seen from the inside. Fig. 2 is a cross-section through the window along the line X 15 X of Fig. 1. Fig. 3 is a horizontal section taken through the window in the direction of the lines Y Y of Fig. 1, with one casement opened outward. Fig. 4 likewise shows a horizontal section taken along the line Y' Y' 20 of Fig. 1, with one casement of the improved window when the lower window grooved bar, a, is taken out and the casement b is opened inward. Fig. 5 shows, on a larger scale, a section taken through the double hinge g of 25 the casement. Fig. 6 shows, on a larger scale, the special construction of the sockets c and e of this double hinge in such a position that the slanting edges a' b', running one upon the other, are justlying together, a position which 30 the parts assume when the window is closed or opened outward. Fig. 7 shows the position of the parts of the hinge, Fig. 6, at right angles to the position of Fig. 6. Fig. 8 shows the boxes or sockets of the hinge parts when 35 the upper part, c, thereof is slid down on the incline d of the lower socket, e, so that the casement is lowered to the height of its edge f down on the casement, Fig. 2, a position which is assumed when the window is opened 40 inward.

The object of this invention, hereinafter described, is to make windows in such a way that they can be opened both inward and outward, but at the same time to combine this 45 possibility with the condition of obtaining a tight connection between the window-frame and the closed-window casements. In order to attain this purpose, each of the casements has two separate points of rotation, and in 50 addition the double hinges of the casements are so made that the casements when opened

inward descend and the lower window-bar is made to take off, so that the casement provided with a strip at its bottom can be drawn inward through the space thus cleared. 55

The casements b b are attached to the window-frames h h by double hinges g g. The window-frame h h has at the bottom grooved surfaces i i, on which the lower window-bar, a, is laid. The regular or irregular grooves i 60 serve to prevent as much as possible the draft getting into the room.

The lower window grooved bar, a, is made of two parts, a² a³, which are also provided with grooves at their corresponding adjoining edges and fit into each other toothwise, so that the entrance of draft is prevented. The lower window-bar has two curved ends, a⁴, which fit into sockets in the window-frame h. In this way a secure and excellent air-tight and easily-separable connection between the window-bars is obtained. a⁵ is an appliance for holding one casement so that the closed casements cannot fly outward. 70

The casements are, as already stated, attached to the window-frames by double hinges g g g g. The double hinges are shown on a large scale in Figs. 5 to 8. One flange of the hinge is attached to the inner side of the casement at g'. The other flange, g², runs in a 80 bent form to the outer side of the window-frame h, and there rotates about the hinge-flange g³, fastened to the window-frame.

If now one casement is to be opened, it is turned about g³ and pressed outward, so that 85 it comes into the position shown in Fig. 3. If both the casements of one window are thus moved outward, it is easy to take out the lower window-bar, a, separated into its two parts, a² a³. If it is now desired to open the 90 windows inward, they are turned about the part g', as shown in Fig. 4, and they can then be opened inward. The hinge parts g', with which the double hinges g are attached to the windows, have tubular sockets c, Figs. 6 to 8, 95 which for the greater part of their circumference are cut off obliquely or spirally. The same applies to the tubular sockets e of the hinge parts g², cut off obliquely at d. The object of this arrangement is to lower the 100 window to a certain extent while turning about the hinge g', the said extent being

just what the flange *f* amounts to on the casement. As appears from Figs. 1 and 2, the casements are provided at *f* and *k* with strips or flanges, the object of which is to effect a secure air-tight closure of the window against the window-frame or lower window-bar, *a*. The height of the upper flange, *f*, and the descent of the casement on the oblique surface *d* are less than the space between the strip *k* and the grooves *i*, so that when the casement is lowered it can pass freely inside the frame without striking any obstruction at the top or bottom. If now, upon moving the outward-turned casement *b* inward from the position Fig. 3 to the position Fig. 4, the edge *b'* of the case *c* on the casement comes beyond the edge *a'* on the socket *e* of the hinge-part *g'*, the edge *b'* slides on the oblique surface *d* of the hinge-part *g'* downward, and consequently the casement *b* sinks a little more than the height of the flange *f*, so that the flange *f* of the window moved inward comes and lies inside the window-frame *h*. The inward movement of the casement is thus, in spite of the arrangement of the flanges *f* and *k*, rendered possible as soon as the lower window-bar, *a*, is taken out of the window-frame.

In order to prevent water from collecting on the windows and running down them into the lower bar, *a*, and also to prevent the casements in winter from being frozen in, a lip,

l, is fitted to the inside of the window-casements below the panes, which catches the water and prevents its running down into the 35 lower grooved bar.

Between the casement and the window-frame or the lower window-bar india-rubber or other packing can be placed for the purpose of tightening the casements.

What I claim, and desire to secure by Letters Patent of the United States, is—

1. The combination of a double-acting hinge, one of whose joints or hinge-points is made with spiral or inclined bearings, a casement 45 hinged thereto, and a removable bottom strip arranged in the opening at the bottom of the casement for the latter to close against, substantially as and for the purpose described.

2. The combination of a double-acting hinge 50 having inclined bearings at one of its articulations, a casement hinged thereto, a removable bottom strip for the lower part of the casement to bear against, and a lip, *l*, attached to the lower part of the casement and overhanging the removable bottom strip to catch the condensed water on the casement, substantially as and for the purpose described.

In witness whereof I have hereunto set my hand in presence of two witnesses.

GUSTAV JOSEF DOLLINER.
